(Cl. 92—68)

This invention relates to the manufacture and handling of paper, cardboard, and similar materials and has particular reference to the addition of moisture thereto for controlling their physical properties and/or other characteristics.

In the past, various methods have been used to apply moisture to moving paper webs for the purpose of increasing their moisture content, of increasing the ease of finishing, of influencing the tendency of the paper to curl, or for other purposes. Various types of sprays have been used but with these there has been difficulty in securing the uniformity and the freedom from spotting by water drops desired on many types of paper.

Steam showers have often been used instead of water sprays. These have commonly consisted of means for discharging steam into the air in immediate proximity to, commonly just below, the moving web. They were frequently formed by a series of equally spaced holes in a steam pipe extending across the width of the web, though various types of refinements in construction were often added to improve the performance of the device. Such showers would frequently blow drops of condensate onto the web, thus objectionably marking some types of paper. Though various methods were often adopted to prevent this, such showers seldom gave complete satisfaction. Stray air currents would often disturb or dilute the ascending steam and cause irregular distribution of moisture on the paper. Possibilities of accurate control were lacking and results were not uniformly dependable.

Sweat rolls have also been frequently used, most often at the end of the dryer section of a paper making machine. These are rolls which are kept cool by internally circulating cooling water, or by other means, and on the surface of which water condenses from the usually humid atmosphere surrounding the machine. As the paper passes around these rolls the film of condensed moisture is transferred thereto. If the humidity in the room was too low to condense the desired amount of moisture on the rolls, steam showers were sometimes placed to discharge steam into the atmosphere adjacent these rolls and thus increase the amount of moisture which would condense thereon. This was not always satisfactory as variable air currents would often blow the steam away from parts of the roll and thus cause uneven moistening of the web. Attempts to enclose the device to prevent the deleterious effects of stray air currents resulted in almost pure steam within the enclosure and therefore often caused the condensation of more water than was

desired or than could safely be applied to the paper web.

The primary object of the present invention is therefore to overcome these and other disadvantages of the various methods and devices of the prior art, and to provide a method and apparatus by which it is possible to apply controlled amounts of moisture to travelling webs of paper and to secure substantially even distribution of the applied moisture over the surface of the web. Another object of the invention is to provide a method and means by which the amount of moisture being added to the web may be readily and quickly adjusted when adjustment is desired. 15 Other objects of the invention will become apparent from the following description.

For the accomplishment of these objects I use steam as the source of moisture. I find that I can control the amount of water condensed from 20 steam by mixing air therewith in definite, controlled, and preferably adjustable proportions, to form a substantially homogeneous unsaturated mixture. The term "unsaturated" as herein used means that the mixture contains less water than 25 it could contain in the form of vapor at that temperature and pressure. The larger the proportion of air the less water will condense from the mixture onto any given object, such as a sweat roll or a web of paper, and vice versa. 30 When using such a controlled mixture instead of steam alone, I find that the condensation is rendered uniform and constant, instead of being unduly increased, by the use of enclosing housings which shield the mixture from extraneous air 35 currents. Results are also improved by passing the mixture over the condensing surface at considerable velocity, that is a velocity sufficient to maintain the quality of the mixture (i. e., the proportions of steam and air therein) at an approximately constant value throughout the space 40 adjacent the condensing surface by displacing the mixture as rapidly as its moisture content becomes depleted due to condensation, by maintaining a turbulent flow to prevent local depletion near the condensing surface, and by preventing significant variations in flow due to neighboring air currents, the movements of the surfaces, etc. I also find it advantageous to heat the mixture 45 and/or its component parts so that the water vapor therein will be in a somewhat superheated state, and fog and water drops will not be present therein.

Water from this mixture will condense upon an object it touches, which has a temperature 50 below the dew point of the mixture. This may

be the paper to be moistened or it may be a sweat roll which transfers the condensed moisture to the paper. In case only temporary moistening, as for the control of the tendency of the paper to curl, if desired, no cooling is required, and when the paper passes from the moistening device into the air the heat of condensation serves to almost immediately evaporate most of the condensed water, leaving the moisture content of the web substantially unchanged. If, on the other hand, it is desired to increase the moisture content of the web, it is necessary to remove the heat of condensation before it has opportunity to cause re-evaporation. This can be accomplished in various ways. For example, when the water is transferred to the paper from a sweat roll, the cooling medium in the roll carries away the heat of condensation; alternatively, the web can be cooled, as by passing over a chilled roll, before it contacts the steam-air mixture. Advantageously, however, a chilled roll, or other cooling medium is used to abstract heat from one side of the web while the other side of the web is in contact with the steam-air mixture.

The invention will be further described in connection with the accompanying drawings, in which:

Fig. 1 is a diagrammatic illustration, partly in section of one form of device for uniformly distributing the steam-air mixture over the surface of a web, for increasing the moisture content thereof.

Fig. 2 is another view of the same device shown partly in section as indicated by line 2-2 in Fig. 1.

Fig. 3 is a diagrammatic view of similar devices arranged to increase the moisture content of a web by applying moisture to both sides thereof, showing the connections to steam, air, and cooling water supplies.

Fig. 4 is a sectional view of another form of device, adapted primarily for the temporary application of moisture to one side of a paper web to correct the tendency of the paper to curl.

Fig. 5 is a sectional view taken on line 5-5 of Fig. 4.

Referring to Fig. 1, a paper web 10 passes around a roll 11 from which heat is abstracted by water which enters and leaves the roll through pipes 12 and 13, respectively, by means of a conventional packing box 14, and under control of valve 15. The steam-air mixture enters through a pipe 21, of ample diameter, and is uniformly distributed across the full width of the web to be treated, by a series of uniformly spaced holes 22, through which it escapes into a housing 23. One wall 24 of this housing lies closely adjacent and roughly parallel to the surface of web 10 on roll 11, and is provided with an opening 25 which extends across the face of the roll, and through which the mixture passes into contact with the web and thence circumferentially around the roll in both directions through passageway 26 between the roll and the wall 24. The other wall 27 of housing 23 is advantageously provided with thermal insulation 28 for preventing unnecessary loss of heat and condensation on the wall 27. Partition members 29 may advantageously be provided in housing 23 (see Fig. 2) to divide the housing into sections and thus strengthen the structure and at the same time prevent undesirable cross currents in the steam-air mixture, which might interfere with its uniform distribution across the web. The end members of housing 23 may, if desired, be extended over the

ends of the roll 10 as shown at 30 in order to keep extraneous air currents out of passage 26. Also the passage 26 is made sufficiently thin and the rate of flow of the steam and air through it is maintained sufficiently rapid that turbulence is maintained and extraneous air currents have substantially no effect on the flow of the mixture over the paper surface. The term "thickness" as herein used to refer to the passage 26, is used to refer to its least dimension. It is that dimension at right angles to the direction of flow of the steam-air mixture through the passage which is measured radially to the roll 11. By the "width" of the passageway is meant that dimension measured at right angles to the direction of flow of the mixture therethrough, which is measured parallel to the length of roll 11 and in the same direction as the width of the paper web. The "length" of the passageway 26 is correspondingly measured in the direction of flow of the mixture therethrough, i. e., circumferentially of the roll 11, and lengthwise of the web. As is clearly shown in the drawings, this length of the passageway is great in proportion to its thickness in order to give full effective contact of the mixture with the surface along which it flows and on which moisture therefrom is to condense.

Fig. 3 shows two such devices for applying moisture in succession to the two sides of the web 10. Their construction and function are as described in connection with Figs. 1 and 2. Fig. 3 shows also one type of means for providing the desired mixture of steam and air. In this case air is supplied under pressure by a rotary compressor 40, or other suitable device, and is delivered through pipe 41 and branch pipes 42 under control of valves 43 to the shower pipes 21, already described. Means may be provided for heating this air to aid in preventing the formation of fog when steam is added. For this purpose a steam jacket 44 may be provided around pipe 41. Steam under pressure is supplied to this jacket through pipe 45 under control of valve 46. Condensate is removed through a pipe 47 and trap 48.

Steam for the mixture is supplied from a steam pipe 50 through pipe 51 and branch pipes 52 which inject steam, under control of valves 53, into the air flowing through pipes 42. Provision may also be made for superheating this steam to assist in preventing the formation of fog. This superheater may also take the form of a steam jacket 54 surrounding the pipe 51. Steam, under higher pressure than that in pipe 50, is supplied to this jacket through pipe 55 under control of valve 56 and condensate is removed through pipe 57 and trap 58.

The operation of the device is as follows: The air supply is turned on and heated as desired by opening steam valve 46. The valves 43 are opened to admit cooling water to the rolls 11. The paper web 10 is threaded through the device as shown in the figure. Then steam is admitted by opening valves 53 to the desired amount. The valve 56 may also be opened to provide superheat in the steam. The openings of the valves 15, 43 and 53 are adjusted until the tests of the web show that the desired amount of moisture is being added. Thus, although the proportions of steam and air in the mixture (as related to the speed of the web, the temperature of, and the rate of heat transfer through the shells of rolls 11) determine the amount of moisture added to the

web, it is not necessary to know these proportions. The valves are simply set on the basis of the results obtained. Other things being equal, it is desirable to add the same amount of water to each side of the web. Sometimes, however, it may be desirable to add more to one side or the other, or even to moisten one side only, in order to control the tendency of the web to curl, or for other reasons. This also can be accomplished by setting the valves to give the desired results. If at any time the web breaks and is not immediately re-threaded around the rolls 11, it is desirable to turn off the steam so the air comes to rolls 11 warm and dry, and then to turn off the cooling water and stop its circulation through the rolls 11. This prevents the accumulation of water on the surfaces of these rolls and leaves them clean and dry so that the paper web may be readily threaded around them.

With the device as illustrated in Figs. 1 to 3, uniformity of results depends on uniformity of the paper speed over the cooling rolls. At the end of the dryer section of a paper machine, however, where this device is most commonly located, the paper speed is substantially constant and any changes in speed would require re-adjustment of the device even though its action were unaffected by the change.

In order to facilitate threading and the removal of broken paper from the passages 26, the housings 23 may, if desired, be swivelled to swing away from rolls 11 during the threading and cleaning-up operations. Furthermore, in order to prevent broken paper from getting into housings 23 through the openings 25 these openings may be advantageously covered with a screen or grille, not shown. Care should also be taken to see that the steam is admixed with the air in such a manner, and far enough before it reaches the housings 23 that no stratification occurs and the mixture in housings 23 is substantially homogeneous throughout, in order to assure uniform distribution of moisture over the surface of the web.

Figs. 4 and 5 show another embodiment of the invention as applied to the temporary application of moisture to one surface of a web in order to control the tendency of the paper to curl. In this case it is not necessary to abstract heat from the web 60 which, after passing around a roll 61, passes over two fixed, smooth, and substantially co-planar straight edges 62 and 63 which constrain the web to travel in a substantially plane path between them. The steam-air mixture enters through pipe 71 and is uniformly distributed across the width of the web by a series of uniformly spaced holes 72. These are here illustrated as formed in a series of corrosion resistant screws 73 which enter the pipe 71 from below and extend upward for some distance inside of the pipe to entrap any condensate which may come through pipe 71, especially when starting operation of the device. One or two screws beyond the edges of the web 60 are short and allow the condensate to be blown out where it will not reach the paper. The steam-air jets strike the slanting lower wall 74 of housing 75 and any entrained condensate flows downward and escapes through a drain 76. The mixture then flows upward and outward through a narrow slit 77 formed between plates 78 and 79 and extending across the full width of the web to be treated. Partition walls 80 serve to maintain the spacing of plates 78 and 79 and to direct the flow and prevent cross currents and eddies which might interfere with the even distribution of the mix-

ture across the web. The mixture then flows downward through a substantially uniform passageway 81 between the web 60 and the adjacent exterior wall 82 of the housing 75, and finally escapes into the atmosphere at 83. Steam passages 84, 85, and 86 are provided for heating plate 78, plate 79 with straight edge 63, and straight edge 62, respectively, to a temperature above the dew point of the steam-air mixture, in order to prevent condensation of water at points where it might be blown or otherwise transferred onto the paper web. A layer 87 of thermal insulating material is provided around the walls of housing 75 to prevent unnecessary heat loss and condensation of moisture on the inside surfaces.

The straight edges 62 and 63 serve to exclude extraneous air currents which might otherwise flow along with the paper and interfere with the uniform distribution and flow of the steam-air mixture in passage 81 along the surface of the web 60. The entrance of disturbing air currents from the edges is prevented by the end walls 88 of the housing 75. When the web 60 is narrower than the housing 75 as shown in Fig. 5 adjustable shields 91 (not shown in Fig. 4) are provided for enclosing passage 81 beyond the edges of the web. This gives a practically completely enclosed passage through which a substantially uniform distribution and flow can be maintained. The passage 81 corresponds to the passages 26 described in connection with Figs. 1 and 2. The terms "length," "width," and "thickness" are used in a corresponding sense in describing this passage-way 81. It, like passages 26, is at least as wide as the paper web and, as clearly shown in the drawings, is long in proportion to its thickness, for analogous reasons.

The steam-air mixture can be formed and supplied to shower pipe 71 in the manner described in connection with Fig. 3. An alternative method is illustrated in Figs. 4 and 5. In this modification steam is supplied through pipe 101 under control of valve 102 while the air enters through pipe 103 under control of valve 104. The air may be supplied by a pump as shown in Fig. 3 or the mixer 105 may take the form of a steam jet ejector which may serve as pump and mixer combined. From mixer 105 the mixture flows through pipe 106 which divides into branches 107. These branches pass through a steam jacket 108 which serves to superheat the mixture, instead of the two components separately as in the previously described embodiment. Steam is supplied to this jacket through pipe 109 provided with valve 110 and the condensate is removed through pipe 111 and trap 112. The pipes 107 lead, by suitable connections 113, to the opposite ends of shower pipe 71, and keep it filled with the mixture under the low but necessary pressure.

In this case, for any given mixture of steam and air, the amount of water condensed is dependent primarily on the available temperature rise in the web and is therefore relatively independent of variations in the speed of the web, but dependent on the temperature at which the web reaches the device. Uniformity of results, therefore, depends on substantial uniformity of temperature of the web coming to the device. Such uniformity is ordinarily found where a device of this type is used, but changes in web temperature may be made and will ordinarily require a re-adjustment of the percentages of steam and air in the mixture, if changes are not desired in the amount of moisture added.

In case it should be desired to use the device in

the form illustrated in Figs. 4 and 5 for increasing the moisture content of the web instead of for the mere temporary addition of moisture, means may be provided for removing heat. For example, the web may be pre-cooled by providing cooling for the roll 81 similar to that used in rolls 11 (Figs. 1-3). Or heat removal could be accomplished by passing a current of cooled air over the side of the web 80, opposite to that exposed to the steam air mixture in passage 81. Alternatively the member 82 and passage 81 may be made curved to follow paper on the surface of roll 11.

Whatever form the device may take, however, I find that the present invention furnishes a simple and effective method and apparatus for uniformly and either temporarily or permanently adding moisture to fibrous webs such as paper, and for accurately controlling the operation to give, within limits, whatever degree of moistening may be required.

I claim:

1. A device for applying a controlled amount of moisture to a moving web of paper by a process involving condensation of the required moisture from an unsaturated mixture of steam and air, which comprises: means for constraining the web to travel in a fixed path at the location where the moisture is to be applied thereto; means for continuously forming an unsaturated mixture of steam and air; means for adjusting the proportions of steam and air mixed by said mixing means; a housing extending across the width of the paper web, for maintaining a quantity of said mixture under pressure slightly above that of the surrounding atmosphere; conduit means for continuously conducting said mixture from said mixing means to said housing; a wall member associated with the housing and disposed closely adjacent and substantially parallel to the position of the condensing surface, said wall and said condensing surface defining a thin passageway, which is long in proportion to its thickness and at least as wide as the paper web, for conducting a stream of said mixture along said condensing surface lengthwise of the web, said wall member further constituting means for directing and confining said stream of mixture to, and excluding extraneous air from, said passageway; and escape means in said housing, extending uniformly across the width of the web and communicating with said passageway, through which said mixture flows, uniformly distributed across the width of the web, from said housing into said passageway.

2. A device for applying a controlled amount of moisture to a moving web of paper by a process involving condensation of the required moisture from an unsaturated mixture of steam and air, which comprises: a roll in contact with which the moving web travels; means for continuously

cooling said roll; means for continuously forming an unsaturated mixture of steam and air; means for adjusting the proportions of steam and air mixed by said mixing means; a housing extending across the width of the paper web, for maintaining a quantity of said mixture under pressure slightly above that of the surrounding atmosphere; conduit means for continuously conducting said mixture from said mixing means to said housing; a wall member associated with said housing and disposed closely adjacent and substantially parallel to the surface of said roll, said wall and the surface of said roll defining a thin passageway which is long in proportion to its thickness and at least as wide as the paper web, for conducting a stream of said mixture circumferentially along the surface of said roll, said wall member further constituting means for directing and confining said stream of mixture to, and excluding extraneous air from, said passageway; and escape means in said housing, extending uniformly across the width of the web and communicating with said passageway, through which said mixture flows, uniformly distributed across the width of the web, from said housing into said passageway.

3. A device for applying a controlled amount of moisture to a moving web of paper by condensation thereon of the required moisture from an unsaturated mixture of steam and air, which comprises: two fixed smooth straight edges over which the paper travels and which constrain the web to travel in a substantially plane path therebetween; means for continuously forming an unsaturated mixture of steam and air; means for adjusting the proportions of steam and air mixed by said mixing means; a housing extending across the width of the paper web, for maintaining a quantity of said mixture under pressure slightly above that of the surrounding atmosphere; conduit means for continuously conducting said mixture from said mixing means to said housing; a wall member associated with said housing and disposed closely adjacent and substantially parallel to the surface of the web as it passes between said straight edges, said wall and the surface of the paper web between said straight edges defining a thin passageway which is long in proportion to its thickness and at least as wide as the paper web, for conducting a stream of said mixture lengthwise along the surface of the web, said wall member further constituting means for directing and confining said stream of mixture to, and excluding extraneous air from, said passageway; and escape means in said housing, extending uniformly across the width of the web and communicating with said passageway, through which said mixture flows, uniformly distributed across the width of the web, from said housing into said passageway.

DONALD B. BRADNER.
